UNITED STATES PATENT OFFICE.

CORTLAND WOODBURY DAVIS, OF CHICAGO, ILLINOIS, ASSIGNOR TO THE MANTLE LAMP COMPANY OF AMERICA, OF CHICAGO, ILLINOIS, A CORPORATION OF ILLINOIS.

BURNER.

1,254,581.

Specification of Letters Patent. Patented Jan. 22, 1918.

Application filed December 22, 1913. Serial No. 808,238.

To all whom it may concern:

Be it known that I, CORTLAND W. DAVIS, a citizen of the United States, residing at Chicago, in the county of Cook and State 5 of Illinois, have invented certain new and useful Improvements in Burners; and I do hereby declare the following to be a full, clear, and exact description of the invention, such as will enable others skilled in 10 the art to which it appertains to make and use the same.

This invention is an improvement in burners for lamps or stoves of the blue flame type, having a central draft, more 15 particularly of that type adapted to burn a liquid hydro-carbon for the production of heat or light, and relates particularly to the flame spreader or air distributing means for distributing air into the hydro-carbon 20 vapor as it rises from the fuel carrier or wick.

It is generally known that certain hydro-carbon fuels when converted into a vapor require relatively large quantities of air, in 25 order to effect their complete combustion resulting in a nonluminous or blue flame. Furthermore, in hydro-carbon burners of the Argand type the draft from any fixed size of chimney varies with the heat generated from the combustion of the fuel, and that when the flame is turned low the draft is correspondingly weakened and the velocity and volume of air introduced to the flame are reduced. In this case there is a 35 tendency for the blue flame to change to a luminous flame, on account of the insufficient air introduction for complete combustion.

It is a common practice in blue flame 40 burners of the Argand type, especially that class adapted to an incandescent mantle where a fuel carrier such as a wick is used, to maintain a non-luminous combustion when the wick is turned low by preventing the air from striking the end of the wick. This tends to cause the flame to be separated 45 from the wick when the wick is low, and so prevents excessive heating and consequently reduces the amount of hydrocarbon 50 produced; therefore, the proportion of air to hydrocarbon is greater, and a blue flame is produced. In other words, the low blue flame is maintained by turning down the wick and restricting the air from the wick. 55 A common means of restricting air from

the wick when set low in burners of this class is to employ a horizontal flange around the upper extremity of the outer wick tube and a flame spreader in coöperative relation with the inner wick tube, the spreader being without perforations low enough to admit air to the wick when it is turned low.

One of the defects in air distributors or flame spreaders used in burners of this character previously known to me, especially of 60 the Argand type adapted to incandescent lamp mantles where a fuel carrier such as a wick is used, is that such spreaders either do not restrict air enough from the wick when low, or do not admit air enough to a wick 65 set high to produce a high or normal operating flame, thereby greatly reducing the operative range of flame that may be obtained from the burner and giving a flame inclined to be luminous at either the low 70 or high position of the fuel carrier, or both.

One object of this invention, therefore, is to overcome the foregoing defect in previous burners of this type, and to introduce more air to the flame when turned high, 80 and restrict the air supply when the flame is turned low. A further object is to reduce the heat of conduction and radiation transmitted to the fuel carrier tubes. Further purposes of the invention will be observed from the details in the description 85 thereof.

The invention comprises a burner having a spreader with a frusto-conical top, the frusto-conical section and the upper part of 90 the body section being perforated for air passage.

The invention consists also in the features of construction and combination of parts to be hereinafter described and particularly pointed out in the appended claims.

In the accompanying drawings, I have illustrated a preferred embodiment of the invention, but the construction shown herein is to be understood as illustrative, only, 100 and not as defining the limits of the invention.

Figure 1 is a side elevation with the gallery removed.

Fig. 2 is a vertical sectional view through 105 a burner constructed in accordance with the invention.

Fig. 3 is an enlarged partial sectional view showing a flame turned low.

Fig. 4 is a view similar to Fig. 3 illus-

trating the flame turned high, or at its operative position.

In the embodiment of the invention, illustrated in the accompanying drawings, the 5 invention is shown applied to a lamp burner, indicated at 5. The burner is provided with an inner tube 6 and a burner cone 4. The fuel carrier or wick is indicated at 8 and is adapted to be secured to suitable elevating 10 mechanism 9, shown in the form of a slide-able sleeve mounted between the inner wick tube 6 and an outer wick tube 10. Any suitable mechanism may be employed to raise and lower the sleeve and retain the 15 sleeve in a predetermined position. The outer tube 10 is preferably bent at 11, or contracted, toward the inner tube 6.

The flame spreader, which is an essential feature of the invention, indicated at 12, and 20 is shown in Figs. 1 and 2 as comprising a substantially imperforate cylindrical wall, indicated at *a*, the upper part of which is shown provided with a plurality of rows of perforations, indicated at 13. Any number 25 of rows of these perforations may be employed, as may be found desirable. It is preferred to so position one row of perforations with relation to its next adjacent row, that the perforations will be staggered with 30 relation to each other, thereby leaving small bridges of metal to connect the walls with the top. The top of the spreader is shown as substantially frusto-conical having the closed top plate *b*, which is preferably im- 35 perforate, and which is preferably at right angles to the wall *a*. The top plate *b* is connected to the side wall *a* by the inclined wall indicated at *c*. A plurality of perforations 14 are provided in the wall *c*.

40 The side walls *a* of the spreader are adapted to rest upon the stop flange 7 of the inner tube 6, for the purpose of retaining the spreader in operative position, and at the same time permit its ready removal from the 45 burner for the purpose of cleaning the parts.

The inclined wall *c* at the top of the spreader may be at any desired angle with relation to the side walls *a*. For example to produce proper effect on the flames of cer- 50 tain types of burners, this wall *c* may be positioned at approximately thirty-five degrees with relation to the horizontal wall *b*.

The air from the inner tube 6 is permitted to flow over the wick through the perfora- 55 tion of the flame spreader, indicated at 12, a part of the air so introduced flowing sub- stantially horizontally through the side perforation 13 of the spreader, and the remain- der of the air passing out obliquely through 60 the perforated frusto-conical section 14. The efflux efficiency of the oblique perforations 14 is greater than that of the horizontal perforations 13, as they permit of a more direct escape for the air from the inner pas- 65 sage formed by the tube 6. The horizontal

projections of the oblique perforations 14 being directly over the introduction of air to the side perforations 13, tends to decrease the efflux efficiency of the side perforations. This is especially true when the flame is 70 turned low and the draft correspondingly weak. Under such conditions a large percentage of the air passes through the perforations 14 and not into contact with the low flame. (See Fig. 31.)

75 The bottom row of perforations 13 in the spreader may be positioned at any desired point near the end of the inner wick tube to obtain the proper results when a flame is turned low. The top row of perforations 80 in the wall *a* is preferably positioned substantially in alignment with the top or horizontal flange 16 of the cone cap, as shown in Fig. 2.

85 In operation, assuming the fuel carrier to be in the form of an ordinary wick, the wick being carried between an inner tube 6 and outer tube 10 and thence upwardly until the top of the wick is slightly above the ends of said tubes 6 and 10. The wick carrying the 90 hydro-carbon fuel may now be ignited and the exposure of the wick being relatively small, the flame will of course be found correspondingly small. In the case of a low flame, the nonluminous combustion is main- 95 tained by decreasing the volume of hydro-carbon vapor given off from the wick, turning down the wick and by restricting the air from the wick. By reference to Fig. 3 it will be seen that air from the outside air 100 passage 15 is restricted by the annular horizontal flange 18. Air from the passage within the tube 6 passes principally through the oblique perforations 14, as indicated by the directions of the arrows, over the small 105 flame, the small proportion of air necessary to be supplied to maintain a non-luminous combustion passing through the perforation 13 to the flame. In Fig. 4 the wick has been raised to its operative position. The in- 110 creased exposure of wick-surface gives off more hydro-carbon vapor. The flame is higher, and larger in size, and requires a larger amount of air for the complete com- bustion of the fuel. In this figure the air from the perforation 14 enters into the 115 flame, as indicated by the arrow, and assists in the combustion of the fuel. The air through perforations 13 and 14, together with the outside air introduced through the 120 passage 15, maintains a non-luminous com- bustion. It will therefore be observed that the flame spreader admits of a part of the inside air to the combustion with the burner being turned to a low flame and all the in- 125 side air to the combustion when the flame is turned high.

130 With reference to the radiation and con- duction of the heat from the flame to the wick tube by the flame spreader, it will be

observed that the top section of the flame spreader 12 has the perforations 14 near its periphery. The area of metal in this top is therefore less than would be the case for 5 the top of a common thimble spreader with no perforations in its top. Because of the decreased area of the top to be exposed to the heat of the flame, the flame spreader with the top perforations absorbs less heat, 10 and consequently has a smaller amount to dissipate to the wick tube which supports the spreader.

It will be observed also that the oblique perforations 14 introduce air to the flame at 15 a point above their horizontal level, in fact above the level of the top plate *b* thereby permitting the position of the flame spreader to be comparatively lower than would be possible with a spreader of this class not 20 provided with the oblique air admission apertures. One advantage of this construction is that on account of the flame spreader being comparatively low, it absorbs a less amount of the heat from a flame than 25 would a flame spreader positioned higher up, consequently, the flame spreader constructed in accordance with this invention would be cooler and dissipate less heat to the wick tube within which it is supported. In the 30 ordinary type of burner and flame it not infrequently happens that the flame from the wick is much higher than the flame spreader and overlaps the top of the spreader forming a partial vacuum between 35 the outer edge and central portion of the spreader causing the flame to curl in and impinge directly over the top of the spreader, thereby excessively heating the spreader and increasing the conduction of heat to the wick 40 tube. This objectionable feature is obviated by introducing air through the perforations 14 obliquely against the flame.

Having thus described my invention, what I claim as new and desire to secure by Letters Patent is:

1. In a central draft burner of the blue flame wick type, including a burner cone having a substantially horizontal flange at its upper extremity, a wick, a wick tube, and 50 a flame spreader mounted on the wick tube to have a portion thereof extend above the horizontal flange of the burner cone, said flame spreader having a tubular perforated body portion adapted to closely fit within the 55 wick tube, and a frusto-conical portion, above the flange of the burner cone, said top portion having an oblique annular portion provided with an annular row of perforations for the admission of air obliquely to 60 the flame of the wick above the flange of the cone.

2. A flame spreader for central draft burners of the blue flame wick type, comprising a cylindrical perforated body section 65 and a frusto-conical top section, the base of

which is of substantially the same diameter as the cylindrical body section, the oblique portion of the frusto-conical top section having a circumferential row of perforations, the perforations of the body section 70 and of the top section being contiguous.

3. A blue flame burner of the wick type comprising a burner cone, a wick tube, a wick, and a flame spreader mounted on the wick tube, said flame spreader having an 75 imperforate horizontal top and a cylindrical wall provided with a plurality of rows of perforations extending from a predetermined point in the cylindrical wall toward the imperforate top to admit air to a flame 80 whether set high or low, and a straight annular wall connecting the top plate with the cylindrical wall positioned on a plane above the top of the burner cone, said annular wall being provided with a row of perforations 85 to permit air to pass from the interior of the spreader obliquely into a flame when set high and over a flame when low.

4. A central draft burner comprising a burner cone having an inwardly directed annular horizontal top flange and a freely open flame spreader positioned in co-operative relation to said burner cone, said flame spreader having a frusto-conical top portion provided with a row of perforations 95 positioned above the plane of the annular flange of the burner cone.

5. A flame spreader comprising a tubular, cylindrical body, the outer face of which is unobstructed, said body being provided with perforations at its upper portion, and a frusto-conical portion having an imperforate horizontal top plate and an oblique annular portion provided with a row of perforations which extend circumferentially 105 around the said spreader in said oblique portion thereof.

6. A burner of the blue flame type comprising an inner wick tube, an outer wick tube, a burner cone having a horizontal top member adapted to be positioned on a plane above the upper ends of said wick tubes, a wick, a substantially cylindrical flame spreader having an inclined upper wall connected with an imperforate top, said flame 110 spreader being positioned in the inner wick tube to have its contracted end extend above the horizontal top of the cone and to thereby form a flame passage between said spreader and cone, the inclined wall of said spreader 115 being provided with a row of apertures to admit air from the inner tube to that part of the flame which extends above the horizontal top of the cone.

7. A central draft burner comprising a 125 burner cone having an annular horizontal inwardly directed top flange, and a freely open flame spreader in co-operative relation to said burner cone, said spreader having a single row of circumferentially arranged 130

perforations to admit air obliquely above the flange of the burner cone.

8. In a burner, a burner cone having a horizontal flange at its upper end, a wick tube, and a flame spreader mounted on the wick tube and provided with a perforated side wall to admit air horizontally to a flame below the horizontal cone flange, and a circumferential row of perforations in an oblique top portion of the spreader, said perforations positioned above the horizontal cone flange and adapted to admit air obliquely to a flame.

9. In a burner of the blue flame wick type, a burner cone having a horizontal inwardly directed flange and a freely open flame spreader, said flame spreader having a single annular row of perforations to admit air obliquely above the burner cone.

10. A burner comprising a wick, an inner wick tube having a stop shoulder formed therein, an outer tube provided with an outwardly extending and concentric horizontal flange near the top thereof to restrict the passage of air to the base of the wick, a cone coöperating with the flange of the outer wick tube to provide an outer air passage, and a removable spreader adapted to rest upon the shoulder of the inner tube, said spreader comprising a side wall, an imperforate top, connected by an annular oblique portion having a circumferential row of perforations therein, the side wall being provided with a plurality of rows of perforations extending upwardly from the top of the wick tubes, thereby providing an inner air passage and permitting air to flow from the inner tube through the side of the spreader to the flame of the wick below the top of the cone and through the perforations in the angular wall to the upper portion of the flame above the top of the cone.

11. An incandescent mantle lamp of the blue flame wick type, comprising a burner cone having an annular and inwardly directed, horizontal top flange, and a flame spreader having a cylindrical side wall and a frusto-conical top, the side wall of the spreader being provided with perforations to admit air horizontally to the flame of the burner below the top flange of the burner cone, the frusto-conical top of the spreader also being provided with a row of perfora-

tions to admit air obliquely to the flame of the burner to spread the burning gases outwardly over the top of the horizontal flange of the burner cone.

12. An incandescent mantle lamp burner of the blue flame wick type, comprising a burner cone having an inwardly directed annular horizontal top flange, an incandescent mantle having its lower end surrounding the outer portion of the horizontal top flange of the burner cone, and a flame spreader having a cylindrical side wall and a frusto-conical top, said spreader provided with perforations in the side wall to admit air horizontally to the sub-flame below the horizontal annular top flange of the burner cone when the lamp is burning low, said spreader also being provided with a row of perforations in the frusto-conical top to admit air obliquely and thereby spread the burning gases outwardly over the horizontal inwardly directed annular top flange of the burner cone and into contact with the mantle during the normal operation of the lamp.

13. A flame spreader for central draft burners of the blue flame wick type, comprising a cylindrical perforated body section and a top section having an inwardly extending inclined portion, the base of which is substantially the same diameter as the cylindrical body section, said inclined portion of the top section having a circumferential row of perforations, the perforations of the body section and of the top section being contiguous.

14. A central draft burner comprising a burner cone having an inwardly directed annular horizontal top flange and a freely open flame spreader positioned in coöperative relation to said burner cone, said flame spreader having an inwardly extending inclined top portion provided with a row of perforations positioned above the plane of the annular flange of the burner cone and near the outer edge of said inclined top portion.

In testimony whereof, I affix my signature in presence of two witnesses.
